UNITED STATES PATENT OFFICE.

OSSIAN HIVELY, OF ALLIANCE, OHIO.

AUTOMATIC ELECTRICAL ACTUATING DEVICE.

Application filed February 14, 1924. Serial No. 692,928.

To all whom it may concern:

Be it known that I, OSSIAN HIVELY, a citizen of the United States of America, and resident of Alliance, county of Stark, and State of Ohio, have invented certain new and useful Improvements in Automatic Electrical Actuating Devices, of which the following is a specification.

This invention relates broadly to electrical control systems, and it has for its primary object to provide a simple and comparatively inexpensive electrical apparatus whereby mechanisms of numerous forms or types may be actuated in accurately timed relation to the movements or actuations of other mechanisms with which they are associated and which, following such actuation, are permitted to assume their normal positions.

20 A further object is to provide an electrical apparatus whereby clutch mechanisms, valves and the like may be shifted through the closing of a therein embodied electric circuit effected through the actuation of an associated mechanism.

In describing the invention in detail, reference is herein had to the accompanying drawing, in which—

Fig. 1 is a diagrammatic view of the invention, illustrating an application thereof.

Fig. 2 is a view of the power cylinder and the operating valve therefor.

While it will be understood that the invention is applicable to various other uses, as the shifting of clutches and other movable elements at predetermined times, it is herein exemplified as applied to the actuation of the traveling conveyors of a sheet bar handling mechanism of the type disclosed in United States Letters Patent No. 1,503,670, dated August 5, 1924, granted to W. J. Stoop, it being herein shown as interposed between the rolls by which, as shown in said patent, the bars are advanced to the transfer table, and the auxiliary power cylinder by which, as shown in said patent, the conveyors are intermittently advanced. In other words, as herein shown, the invention constitutes an electrical means for intermittently rendering operative the power mechanism of said patent, said means including a normally open electrical circuit arranged to be momentarily closed by each sheet bar as a definite point in the advance of the latter.

Referring to said drawings, 1 and 2 indi-

cate the upper and lower rolls of a pair of pinch rolls by which bars, as the bar 3 indicated in dotted lines, are advanced. Having its end suitably pivoted, as in the housings 4 for said rolls, are the opposite ends of a rod or bar 5 having a longitudinal wing 6. Said rod or bar is located on the exit side of and parallel to the rolls and at a suitable height above the level of the pass through the rolls, as shown. The wing 6 normally occupies a vertically depending position, being maintained in such position by the force of gravity. A laterally extending crank arm 7 carried by said rod or bar has pivotally attached thereto the lower end of a substantially upright link 8 which has its opposite end similarly attached to the outer end of a pivoted switch arm 9 which in its elevated, or upwardly swung, position bridges the space between two contact members or plates 10 and 11 located in an electric circuit, and which in its normal lowered position bridges the space between the contact 10 and a contact 12 located in another electric circuit which is normally open.

When the front edge of a bar 3 emerges from the pinch rolls, it strikes against the depending wing 6 of the rod or bar 5 and swings the same to the inclined position shown in dotted lines in the figure, wherein its lower edge rests upon said bar 3. When the rod or bar is so swung, the crank arm 7 is raised, thereby elevating the link 8 and swinging the switch arm 9 to the elevated dotted-line position thereof shown in the drawing. In said position, an electric circuit is completed, which circuit comprises a main conductor 13 leading from a source of electric current to a stationary contact 14 forming a part of a contactor switch of an ordinary type, a conductor wire 15 which branches from said conductor 13, the said contact 11, said switch arm 9, the contact 10, a conductor wire 16, a contact 17, a pivoted switch 18 which, in the normally open position of the pivoted member 19 of the aforesaid contactor switch, connects said contact 17 to a second contact 20, said contact 20, a conductor wire 21 leading from said contact 20, a magnet coil 22 carried by said pivoted switch member 19, a conductor 23 leading from said magnet coil to a post 24 carried on the top of the shell of a solenoid 25, a horizontally arranged metallic plate or strip

26 disposed in seated overlying relation to the armature 27 of said solenoid, said plate or strip having one end pivotally mounted upon an upright lug or post 28 carried on 5 the top of said solenoid and having its opposite, or free, end normally resting upon said post 24, a conductor wire 29 leading from the pivoted end of said plate or strip 26 to a main conductor 30, the latter being 10 connected to the aforesaid source of current.

The closing of the aforesaid electric circuit results in energizing the magnet coil 22 which instantly actuates the pivoted member 19 of the aforesaid contactor switch to swing to a position in which a contact member 31 carried thereby engages the stationary contact 14, thereby effecting closing of a second, or shunt, electric circuit 20 which will hereinafter be described. At the same time, a foot portion 19^a of said switch member 19 resting upon the pivoted switch 18 is swung downward sufficiently to rotate the latter out of bridging relation 25 to the space between the contacts 17 and 20, whereupon the current in said shunt circuit is diverted through a resistance coil 32 interposed between the conductors 16 and 21.

30 The shunt circuit above referred to, closed as aforesaid, comprises the main line conductor 13, the engaged contacts 14 and 31, the pivoted member 19 of the contactor switch, a conductor 33 leading from said member to the conductor 16, the portion of the last mentioned conductor which is disposed intermediate said conductor 33 and the resistance coil 32, said resistance coil 32, conductor 21, magnet coil 22, conductor 40 23, post 24, the pivoted plate 26, conductor 29 and main line conductor 30. The closing of this circuit diverts sufficient current through the energized magnet coil 22 to maintain the engagement between 45 the contact members 14 and 31 when the switch-arm 9 is shifted from engagement with the contact member 11 and bridges the space between contact members 10 and 12, as when the bar 3 has passed from the rolls. Thus, a second shunt circuit is established which comprises main line conductor 13, the engaged contacts 14 and 31, the pivoted contactor member 19, conductor 33, the conductor 16, contact member 10, switch arm 9, contact member 12, a conductor 34 which leads from said contact member 12 to a contact 35, a pivoted switch 36 which bridges the space 50 between said contact 35 and a contact 37, a conductor 38 leading from the last mentioned contact, a magnet coil 39 carried by a pivoted contactor switch member 40 similar to the switch member 19, a conductor 41 leading from said coil and tapped to 55 the conductor 23, said conductor 23, post 60

24, pivoted plate 26, conductor 29 and the main line conductor 30.

The closing of the circuit last above described energizes magnet coil 39 which instantly swings the switch member 40 forward to the position in which a contact 42 carried thereby engages a contact 43 to which is connected the main line conductor 30. When said contact 32 is actuated to engage the contact 43, as just described, a main electric circuit is established, comprising main line conductor 30, contacts 43 and 42, contactor switch member 40, a conductor 44, the coil of the solenoid 25, a conductor 45 leading from said coil to the contactor switch member 40, the last mentioned switch member, engaged contacts 31 and 14, and the main line conductor 13.

The closing of the main line circuit energizes the solenoid 25, actuating the armature 27 of the latter to rise. Said armature is suitably connected, as by a pivoted lever 46 and a connected rod 47, to the valve 48 to be shifted. Consequently, elevation of said armature effects, through the intermediate mechanism, the elevation or shifting of said valve from its normal position to a position admitting fluid actuating pressure to the power cylinder 49. Adjacent to the end of the upward movement of the armature 27 the upper end of said armature strikes the pivoted plate 26 and lifts the free end of the latter from the post 24, thus breaking the electric circuit through the coils of the contactor switches, following 100 which the contactor switch members 19 and 40 instantly swing back to their normal positions, breaking the main line circuit. At the same time, the solenoid armature being released, said armature and the thereto connected valve 48 are free to move to their 105 normal positions.

The switch mechanism comprising the pivoted member 19, magnet coil 22, contacts 14 and 31, pivoted member 18, contacts 17 and 20, and the resistance coil 32 constitutes an ordinary commercial form of contactor switch, as does also the corresponding mechanism which includes the pivoted member 40. The same is also true of the 115 solenoid and overlying pivoted switch member. Therefore, no claim is made to these mechanisms per se.

What is claimed is—

1. In apparatus of the character described, the combination with an element to be actuated, of a solenoid having its armature operatively connected to said element, a switch controlled electric circuit including a pivoted member overhanging said armature, a switch arm for closing said circuit normally disposed out of and shiftable into closing relation to said circuit, a normally open contactor switch having a magnet coil 120 located in and energizable through closing 125

- of said circuit, said contactor switch being adapted to be actuated by energizing of said magnet coil for closing a shunt circuit therethrough, a second normally open contactor switch having a magnet coil located in and energizable through the closing of a second shunt circuit effected by the return of said switch arm to normal position, said second contactor switch being adapted to be actuated by the energizing of its magnet coil to close a main circuit which includes said solenoid and the therewith associated pivoted member, whereby the armature of said solenoid is attracted for actuating the there-
 10 to connected element and also for moving said pivoted member to circuit breaking position.
2. In apparatus of the character described, the combination with an element to be actuated, of a solenoid having its armature connected with said element, a pivoted member located adjacent to said armature, an electric circuit including said pivoted member when the latter occupies its normal position, a shiftable switch-arm for opening and closing said circuit, a pair of normally open contactor switches having magnet coils, the coil of one of said switches being located in said electric circuit and being energizable through closing of said circuit for actuating said one switch to close a shunt circuit, the coil of the other switch being located in and being energizable through closing of a second shunt circuit
 20 effected by movement of said switch arm from its first mentioned position, the last mentioned switch being movable by energizing of its coil to close a power circuit which includes said solenoid and the associated pivoted member, whereby the armature of said solenoid is moved to attracted position for actuating the thereto connected element and for simultaneously shifting said pivoted member to circuit
 30 breaking position.
3. In apparatus of the character described the combination with an element to be actuated, of electrically operated means therefor, a main circuit including said means and a pair of normally open contactor switches, a secondary circuit for each switch and including means to effect the closing of the respective switch and ultimately the closing of the main circuit, an operating switch having a contact in each secondary circuit for alternately closing thereagainst to close the respective circuit, and means operable by said first means for breaking the secondary circuits.
4. In apparatus of the character described, the combination with an element to be actuated, of electrically operated means therefor, a pair of contactor switches each including normally spaced contacts, a magnet coil for closing the contacts and adapted to be electrically connected therewith upon closing of the contacts, a main circuit including said means and said contacts, a secondary circuit for each switch and including the respective magnet coil, said secondary circuits upon being closed energizing the respective coils to effect closing of the main circuit, and a control switch having a contact in each secondary circuit for alternately closing the latter circuits.
5. In apparatus of the character described, the combination with an element to be actuated, of electrically operated means therefor, a pair of contactor switches each including normally spaced contacts, a magnet coil for closing the contacts and adapted to be electrically connected therewith upon closing of the contacts, a main circuit including said means and said contacts, a secondary circuit for each switch and including the respective magnet coil, said secondary circuits upon being closed energizing the respective coils to effect closing of the main circuit, a control switch having a contact in each secondary circuit for alternately closing the latter circuits, and means operable by the first means for breaking the secondary circuits.
6. In combination with element advancing means, energizable work-performing means, means for establishing one side of an electric circuit through said energizable means, other means for completing the circuit through said energizable means, and means engageable by the advancing element for effecting operation of the third means, and operable upon disengagement from the advancing element to render the fourth means operative.
7. In combination with element advancing means, and energizable means for performing work upon said element, means engaged by the advancing element to establish one side of a circuit through said energizable means, means for completing the circuit through the energizable means to thereby energize the latter upon movement of the element out of engagement with the third named means, and means operable by the energizable means for breaking the circuit.
8. In combination with element advancing means, energizable work-performing means, means for establishing one side of an electric circuit through said energizable means, other means for completing the circuit through said energizable means, means engageable by the advancing element for effecting operation of the third means, and operable upon disengagement from the advancing element to render the fourth means operative, and means operable by the energizable means for breaking the circuit.
9. In apparatus of the character described, the combination with an element to

- 4
- be actuated, of electrical means operatively connected to said element, a switch controlled electric circuit including a pivoted member operable by said means, a switch arm for closing said circuit normally disposed out of and shiftable into closing relation to said circuit, for closing a shunt circuit therethrough, a second normally open contactor switch having a magnet coil located in an energizable through the closing of a second shunt circuit effected by the return of said switch arm to normal position, said second contactor switch being adapted to be actuated by the energizing of its magnet coil to close a main circuit through said means and the therewith associated pivoted member, whereby the armature of said means is attracted for actuating the thereto connected element and also for moving said pivoted member to circuit breaking position.
10. In apparatus of the character described, the combination with an element to be actuated, of means for actuating said element, a movable member located adjacent to said means, and electric circuit including said member when the latter occupies its normal position, a shiftable switch arm for opening and closing said circuit, a pair of normally open contactor switches having magnet coils, the coil of one of said switches being located in said electric circuit and being energizable through closing of said circuit for actuating said one switch to close a shunt circuit, the coil of the other switch being located in and being energizable through closing of a second shunt circuit effected by movement of said switch arm from its first mentioned position, the last mentioned switch being movable by energiz-

ing of its coil to close a power circuit which includes said means and the associated member, whereby the aforesaid means is moved to attracted position for actuating the thereto connected element and for simultaneously shifting said member to circuit breaking position.

11. In combination, energizable work-performing means, element advancing means, a normally open contactor switch in circuit with said first means, means operable by an advancing element for closing the switch and the circuit therethrough, other means maintaining a normally open circuit through the first means and adapted to close the circuit therethrough upon disengagement of the element from the third means, and a shunt circuit established by the closing of the switch for maintaining the latter closed following the disengagement of the element from the third means.

12. In combination, energizable work-performing means, element advancing means, a normally open contactor switch in circuit with said first means, means operable by an advancing element for closing the switch, and the circuit therethrough other means maintaining a normally open circuit through the first means and adapted to close the circuit therethrough upon disengagement of the element from the third means, a shunt circuit established by the closing of the switch for maintaining the latter closed following the disengagement of the element from the third means, and means operable by the first means for breaking the circuit.

In testimony whereof, I affix my signature.

OSSIAN HIVELY.
